STOCKING FORM

Ruth B. Doty, Winchester, Mass.

Application December 22, 1932, Serial No. 648,461

13 Claims. (Cl. 223—17)

My present invention relates to devices for use in the stretching, forming and drying of stockings, particularly woolen stockings, the shrinking propensities of which during washing and drying are well known.

An important object of the present invention resides in the provision of a stocking form or stretcher that is simple in the extreme to manufacture and use, economical, and at the same time durable, strong and rugged.

Another feature of my invention resides in the utilization of an openwork stretcher, so that the maximum circulation of air around and through a stocking to be dried will be effected, to dry said stocking in the shortest possible time.

Another object of the invention resides in the fact that my novel stretcher is capable of use in a wide range of sizes, by a simple manipulation to extend the foot portion to the desired size.

One pair of my novel devices, therefore, will suffice for the stretching and drying of stockings within a wide range of sizes, obviating and eliminating the necessity of having a plurality of forms of varying sizes for this purpose.

My novel stocking stretcher may be changed from one size to another in but a moment, it requiring only a simple manual adjustment to effect this change.

Other objects and features of the invention reside in the particular construction and arrangement of my novel device, and all of the above, together with other objects and features of the invention, details of construction, combinations of parts, and advantages, will be hereinafter more fully pointed out, described and claimed.

Referring to the drawing, illustrating a preferred embodiment of the present invention,

Fig. 1 is a side elevation of a stocking stretcher embodying my invention;

Fig. 2 is a rear elevation of said stretcher or form;

Fig. 3 is a fragmentary longitudinal sectional view on the line 3—3 of Fig. 1; and

Fig. 4 is a cross-sectional view on the line 4—4 of Fig. 1.

Referring now to the drawing, for a particular description of the invention, its construction and operation, my novel device comprises a leg portion 1, preferably formed of wire, provided if desired with a loop 2 for hanging or suspending. This wire is preferably of one piece, and is united at one or more points, by cross-arms 3, held in position by the clips 4 or in any other desired manner.

The free ends of the wire 1 terminate at the foot portion, at 5, and to said free ends is attached, as by clamping, a plate 6 provided with a plurality of apertures or recesses 7, spaced at

predetermined intervals to correspond to varying stocking sizes. Said plate 6 is provided with a pair of tubular recesses 8 to receive the ends of a U-shaped extensible toe member 9. One of these ends may be of greater length than the other, to facilitate assembly, as clearly shown in the drawings. In the form of the invention illustrated herein, the plate 6 has its sides curved upwardly and inwardly, to form the tubular recesses to constitute a seat, not only for the arms of the U-shaped toe member, but also for the free ends 5 of the wire or leg portion 1.

The ends 5, however, will be firmly fixed in said tubular recesses, while the arms of the toe member 9 are slideable therein.

Attached to the U-shaped toe member 9, in the bow thereof, by a clamp or clip 10 is a rod or wire 11, which may be, if desired, of slightly less diameter than the wire 1, for ease and facility in manipulation. The free end of the rod 11 is inturned, to provide a button 12 adapted to engage a predetermined recess 7. Said rod 11 is formed, as clearly illustrated, with a finger hold or gripping portion 14, adjacent to the button 12, by means of which the rod 11 may be grasped and the button 12 raised out of its recess.

The operation of my novel device is simple, and will be readily understood, being briefly explained as follows:

It being desired to dry a stocking, said stocking is pulled over said device, the device hung up, and the stocking dried. If, however, the foot portion of the stocking is of a different size to that for which the foot portion is adjusted, the operator simply grasps the handhold 14, raises the button 12 out of its recesses, and slides the U-shaped member 9 toward or from the plate 6, and when the button 12 is in register with the proper recess, releases the handhold 14, whereupon the natural spring of the rod 11 will seat said button 12 in its recess 7 and firmly hold the device in its adjusted position, preventing inadvertent movement thereof.

This device may be made of any suitable or desirable material, or colored or lacquered in any desired finish, as will be readily understood.

The simplicity, neatness, ruggedness, and other advantages of my stocking stretcher or form will be instantly apparent, and since I believe the same is novel, I have therefore claimed said device broadly in this application.

While I have necessarily described my present invention somewhat in detail, it will be appreciated that I may vary the size, shape and arrangement of parts within reasonably wide limits without departing from the spirit of the invention.

My invention is further described and defined in the form of claims as follows:

1. A stocking form, comprising an open leg

portion terminating in a plate constituting a part of the foot portion, said plate having a plurality of size-determining recesses therein, a U-shaped toe portion slideably mounted with respect to said plate, a rod carried by said toe portion and projecting over said plate, and a button at the free end of said rod adapted to engage a predetermined recess to prevent inadvertent movement of said toe portion.

- 10 2. A stocking form, comprising an open leg portion terminating in a plate constituting a part of the foot portion, said plate having a plurality of size-determining recesses therein, a U-shaped toe portion slidably mounted with respect to said plate, a rod carried by said toe portion and projecting over said plate, a button at the free end of said rod adapted to engage a predetermined recess to prevent inadvertent movement of said toe portion, and a handhold
- 15
- 20

20 on said toe adjacent to said button.

25 3. A stocking form, comprising an open leg portion terminating in a plate constituting a part of the foot portion, said plate having a plurality of size-determining recesses therein, a U-shaped toe portion slidably mounted with respect to said plate, a rod carried by said toe portion and projecting over said plate, and a button at the free end of said rod adapted to engage a predetermined recess to prevent inadvertent movement 30 of said toe portion, said rod being provided with an offset portion to constitute a handhold adjacent to said button.

4. A stocking form, comprising an open leg portion terminating in a plate constituting a part of the foot portion, said plate having a plurality of size-determining recesses therein, said plate also having a plurality of tubular recesses adjacent to the sides thereof, a U-shaped open toe portion having arms seated in said tubular recesses and slidably therein to vary the position of said toe portion relative to said plate, a rod carried by said toe portion and projecting over said plate, and a button at the free end of said rod adapted to engage a predetermined recess to prevent inadvertent movement of said toe portion.

portion.

5. A stocking form, comprising an open leg portion terminating in a plate constituting a part of the foot portion, said plate having a plurality of size-determining recesses therein, said plate also having a plurality of tubular recesses adjacent to the sides thereof, a U-shaped open toe portion having arms seated in said tubular recesses and slidably therein to vary the position 50 of said toe portion relative to said plate, a rod carried by said toe portion and projecting over said plate, and a button at the free end of said rod adapted to engage a predetermined recess 55 to prevent inadvertent movement of said toe portion, said rod being provided with an offset portion 60 to constitute a handhold adjacent to said button.

65. A stocking form, comprising an open leg portion terminating in a plate constituting a part of the foot portion, a U-shaped open toe portion slidably mounted with respect to said plate whereby said form with a single toe portion may accommodate stockings of various sizes, a rod extending inwardly from said toe portion and
70. projecting over said plate, and cooperating means on said plate and said rod to hold said toe portion in adjusted position.

7. A stocking form, comprising a leg portion terminating in a plate constituting a part of the foot portion, a U-shaped toe portion slidably

mounted with respect to said plate whereby said form with a single toe portion may accommodate stockings of various sizes, a rod extending inwardly from said toe portion and projecting over said plate, and cooperating means on said plate and said rod to hold said toe portion in adjusted position. 80

8. A stocking form, comprising an open leg portion terminating in a plate constituting a part of the foot portion, said plate having a plurality of size-determining recesses therein, said plate also having a plurality of tubular recesses adjacent to the sides thereof, a U-shaped open toe portion having arms seated in said tubular recesses and slidably therein to vary the position of said toe portion relative to said plate, and means on said toe portion cooperating with said size-determining recesses to hold said toe portion in adjusted position. 85 90

9. A stocking form, comprising a leg portion terminating in a plate constituting a part of the foot portion, said plate having tubular formations adjacent to the sides thereof, a U-shaped open toe portion having arms slideable in said tubular formations to vary the position of said toe portion relative to said plate, and cooperating means on said toe portion and said plate effective to positively hold said toe portion against sliding movement in either direction relative to said plate. 105

105
10. A stocking form comprising leg and toe portions slidably connected for relative adjustment to fit stockings of different sizes, the leg portion including an element having a series of recesses spaced apart corresponding to different form sizes, and a rod carried by the toe portion and extending over said recessed element and having a projection for engagement in a selected recess to hold the leg and toe portions against relative sliding movement. 110 115

11. A stocking form comprising a leg portion, a plate carried by said leg portion, said plate having a pair of tubular formations, a U-shaped toe portion including a pair of arms slidably engaged in said tubular formations for adjustment to vary the size of the form, the plate having recesses spaced apart corresponding to different form sizes, and the toe portion having means for cooperation with said recesses to hold the leg and toe portions against relative sliding movement. 120 125

12. A stocking form comprising leg and toe portions, a plate carried by one of said portions, said plate having a pair of tubular formations, the other portion having a pair of arms slidably engaged in said tubular formations for adjustment to vary the size of the form, one of said portions having formations spaced apart corresponding to different form sizes, and the other portion having means for selective cooperation with said spaced apart formations to hold the portions against relative sliding movement. 135 135

13. A stocking form comprising leg and foot portions, a pair of tubular elements carried by one of said portions, the other portion having a pair of arm elements slidably cooperating with said tubular elements whereby the portions are held in assembly with each other and are relatively adjustable to fit stockings of different sizes, at least one of said portions having formations spaced apart corresponding to different form sizes, and the other portion having means for selective cooperation with said formations to hold the portions against sliding movement.
